DESIGN FOR AN INSTRUMENT BOARD FOR A HAIR WAVING CABINET OR SIMILAR ARTICLE

Monroe F. Dreher, Montclair, N. J., assignor to
The Nestle-Lemur Company, New York, N. Y.,
a corporation of Ohio

Application May 6, 1936, Serial No. 62,490

Term of patent 7 years

To all whom it may concern:

Be it known that I, Monroe F. Dreher, a citizen of the United States, residing in the city of Montclair, county of Essex, and State of New Jersey, whose post-office address is 951 Broad Street, in the city of Newark, county of Essex, and State of New Jersey, have invented a new, original, and ornamental Design for an Instrument Board for a Hair Waving Cabinet or Similar Article of which the following is a specification, reference being had to the accompanying drawing, forming a part thereof.

Figure 1 is a plan view of an instrument board for a hair waving cabinet or similar article embodying my design.

Figure 2 is a side view thereof.

The wavy line finish indicated by the wave like lines shown in portions of the panel is continued throughout the surface of the areas on which it is partially shown.

I claim:

The ornamental design for an instrument board for a hair waving cabinet or similar article as shown and described.

In testimony whereof I have signed this specification.

MONROE F. DREHER.
